UNITED STATES PATENT OFFICE.

JOSE ANTONIO DE CARVALHO, JR., OF RIO DE JANEIRO, BRAZIL.

DENTAL-BLOWPIPE BURNER.

1,253,946.

Specification of Letters Patent. Patented Jan. 15, 1918.

Application filed May 16, 1916. Serial No. 97,866.

To all whom it may concern:

Be it known that I, JOSE ANTONIO DE CARVALHO, Jr., citizen of Brazil, residing at Rio de Janeiro, Brazil, have invented new and 5 useful Improvements in Dental-Blowpipe Burners, of which the following is a specification.

The object of this present invention is to provide an apparatus for the production in 10 quantity and with sufficient pressure, of the gases from alcohol; and for utilizing the heat produced by their combustion.

The principal characteristics of the apparatus is found in the fact that it is able to 15 carry out the works generally done by the employment of carbonic gas, gasoline or kerosene, employing alcohol of 36°.

In the accompanying drawings—

Figure 1 is a perspective view of an apparatus of the character mentioned, constructed and arranged in accordance with the present invention;

Fig. 2 is a side elevation of said apparatus partly cut away to show the interior construction of a portion thereof;

Fig. 3 is a detail view on an enlarged scale showing an inverted cupola to be used in connection with the apparatus herein described.

Fig. 4 shows a slightly modified form of gas chamber and blow-pipe attachment therefor;

Fig. 5 is a detail view in cross section of a distributor for gasifying the liquid under treatment.

Fig. 6 is a detail view in vertical section showing the delivery tube for introducing the liquid to the generator.

The apparatus is provided with the necessary pieces for its working in the ordinary cases. The reservoir for the alcohol, which is shown in the drawing is represented as suspended. In order to supply the apparatus with the air when necessary, it is provided with a small bellows.

In the drawings is provided a metal tube 12 having a valve 13, from which extends a flexible tube 14, preferably of rubber strengthened by a coating of metal.

50 At the extremity of said flexible tube is screwed a metal coupling 15 forming internally a curved conduit 16, having a contracted orifice 17.

Screwed to the coupling 15 around the orifice 17 is a metal nut 18, to which the tube 55 19 is joined, which terminates in a capillary orifice.

The tube 19 may be constructed in such a manner as to terminate in more than one capillary orifice, and these may be arranged 60 in such a manner as to give different directions to the jets of liquid delivered by them.

Fixed by any adequate means to the tube 19 is the cup 20 to which are secured the tubes 21, and the hollow cylindrical support 22. In the circumference of the base of the support are the small orifices 23 and the support is provided with a screw thread. All the above mentioned pieces should be constructed from an appropriate metal. 70

Supported by the tube 19 and partially covering the cup 20, is a metallic concavo-convex disk 24. In the lower part of the coupling 15, there is an orifice engaged by the screw 25, said orifice when open permits 75 of the introduction of a cleaning rod to the tube 19 and the orifice therein, so as to clean them in case of need.

Screwed to the support 22 is a hollow sphere or globe from which the tube 26 extends. This tube shown in the drawings as straight, may be bent. It may also be fixed or movable so that it may empty in the direction the most convenient.

Indicated by the numeral 27 is a blow- 85 pipe supported on the tube 12 by means of a jointed upright 28. The blow-pipe 27 is attached to the rubber tube 29, which is joined to the fixed metal tube 30, so that the displacement of the blow-pipe 27 will 90 not cause by itself the displacement of the tube 30 which has a fixed position on the apparatus. The numeral 31 represents a bar 31 which, in solid union with the blow-pipe 27, serves for giving this latter another 95 fulcrum on the upright 28a.

The braces 32 are parallel to which are joined the parallel plates 33, in which the tubes 12 and 30 are securely fastened. This mounting serves the triple purpose of protecting the blow-pipe against accidental displacement. The braces 32 serve as a handle by which one may carry the apparatus when one desires.

The member indicated by 34 is a support 105 provided with a slot into which screws 35a

extend to engage a metal plate 34^a curved to serve as a wind shield for protecting the globe 35 and parts connected therewith.

The member 34 may be mounted upon or removed from the tube 12 by means of the screw with butterfly nut 36.

The cupola shown in Fig. 3 can be fastened above the globe 35 and upon the member 34 by means of the screw 37.

10 A piece of asbestos cord lightly pressed should be placed in the circular space formed by the cups 22 and 20, so as to fill up that space.

In Fig. 3 cupola 38 has a chimney 39 and 15 projections 40 in its interior, which support the cupola above the globe 35 and at a short distance from the latter.

Fig. 4 shows the globe 35 with the following modifications. The tube 41 serves 20 as an outlet for the gas, and is bent to open upward. The globe 35 has in its upper part, a series of small holes 42 through which escapes a part of the gas generated in globe 35.

The blow-pipe 27 in this view curves like 25 a screw propeller around the globe 35 and terminates in the interior of the tube 41.

A supplementary tube, varying as to dimensions, can be boxed in the extremity of the blow-pipe 27. The same thing may be 30 done as regards the tube.

The construction shown in Fig. 5 may be 35 screwed upon the coupling 43 shown in Fig. 6. Fig. 6 represents a metal coupling 43 in which is a conduit 44. The tube 14 joins onto the nipple 45.

The alcohol runs through a flexible tube 46 which connects a reservoir 47 with the apparatus at the end of the tube 12. The valve 13 being opened, the alcohol runs at once 40 through the conduit 16, orifice 17 and the tube 19 from which it is delivered into the globe 35.

As soon as the asbestos cord around the support 22 appears in a humid state in the 45 inside of the little cup 20 one should ignite the alcohol which oozes therefrom.

The alcohol being ignited, the globe 35 becomes heated, and evaporates the alcohol delivered by the tube which spreads over the 50 internal surface of the said globe. The vapor thus generated is delivered by the tube 26 and the holes 42.

The vapor which escapes through the holes 42 if ignited produces the heat necessary to 55 warm the globe 35 to a temperature sufficient for the continuation of the evaporation of the alcohol, which, in regulated quantity proceeding from the tube 19, is sprinkled over its internal surface. Any small portion 60 of alcohol which accidentally not evaporated, perchance escapes from the support 22 and will fall normally into the tubes 21, where being ignited, it will be consumed.

Forcing a current of air into the blow- 65 pipe 27 and placing it in a convenient posi-

tion in relation to the tube 26 from where the vapor escapes, we have the apparatus in a position proper for producing the necessary heat for the carrying out of the work to which it is designed.

70

I claim:—

1. An apparatus of the character described, comprising a burner, a reservoir, mounted upon the burner and provided with a discharge nozzle, means for delivering the 75 material to be vaporized to the reservoir through the burner, and a blow-pipe having its nozzle at the discharge nozzle of the reservoir.

2. An apparatus of the character de- 80 scribed, comprising a burner, a globe-shaped reservoir mounted on the burner and having a discharge nozzle, means for delivering the material to be vaporized to the reservoir through the burner; a blow-pipe, and means 85 for adjustably holding the blow-pipe with its nozzle adjacent the nozzle of the reservoir.

3. An apparatus of the character de- 90 scribed, comprising a burner, a globe-like reservoir mounted upon the burner and provided with openings in its top and a discharge nozzle in its side, means for delivering the material to be vaporized to the reservoir through the burner, and a blow-pipe 95 held adjacent the discharge nozzle of the reservoir.

4. In an apparatus of the character de- 100 scribed, a supply pipe, a support mounted on the said pipe and provided with a nozzle communicating with the supply pipe, and a globe held on the support and into which the nozzle discharges, said globe having a discharge nozzle.

5. In an apparatus of the character de- 105 scribed, a supply pipe, a cup on the said pipe, a second cup carried by the first cup and adapted to contain an absorbent material, a nozzle projecting through the first cup and in communication with the supply 110 pipe, and a globe mounted on the second cup and having a discharge nozzle.

6. In an apparatus of the character de- 115 scribed, a supply pipe, a cup mounted on the said pipe and having right angular tubes, a second cup carried by the first cup and having openings in its bottom, said second cup being adapted to contain an absorbent material, a nozzle extending through the first cup and communicating with the feed 120 pipe, and a globe mounted on the second cup and provided with a discharge nozzle.

7. In an apparatus of the character de- 125 scribed, a feed pipe, a burner on the feed pipe, an evaporating reservoir mounted upon the burner and having a discharge for the vapor, means for delivering the volatile material to the reservoir, a support carried by the feed pipe, and a blow-pipe mounted in the support.

130

8. In an apparatus of the character described, a feed pipe, a burner on the feed pipe, an evaporating reservoir on the burner and having a discharge for the vapor, means for delivering the volatile material to the reservoir, a support mounted on the feed pipe, a blow pipe and means for mounting the blow-pipe in the said support. 5
9. In an apparatus of the character described, a feed pipe, a burner on the feed pipe, an evaporating reservoir on the burner and having a discharge for the vapor, means for delivering the volatile material to the reservoir, a support mounted on the feed 10 pipe and provided with handles, and a blow pipe mounted in the support. 15
10. In an apparatus of the character described, a burner, a globe mounted on the burner, means for admitting the material to be evaporated to the globe, and a cupola 20 adapted to rest upon the globe in spaced relation thereto.
11. In an apparatus of the character described, a feed pipe, a burner on the feed pipe, an evaporating reservoir on the burner, and having a discharge for the vapor, means for admitting the material to be evaporated to the reservoir, and a support 25 adjustably and removably secured to the feed pipe adjacent the reservoir, said support being adapted to carry a wind screen. 30
- In testimony whereof I have signed my name to this specification in the presence of two subscribing witnesses.
